(Cl. D89—1)

To all whom it may concern:

Be it known that we, Henry J. Talge and Albert M. Travis, citizens of the United States, residing at Kansas City, in the county of Jackson and State of Missouri, and Kansas City, in the county of Wyandotte and State of Kansas, have invented a new, original, and ornamental Design for an Ice Crusher of which the following is a specification, reference being had to the accompanying drawing, forming part thereof, in which

Fig. 1 of the drawing is a plan view of an ice crusher showing our new design,

Fig. 2 is a front elevational view of the ice crusher,

Fig. 3 is a side elevational view of the ice crusher, and

Fig. 4 is a rear elevational view of the ice crusher.

We claim:

The ornamental design for an ice crusher, substantially as shown.

HENRY J. TALGE.
ALBERT M. TRAVIS.
